GEORGE S. GATCHELL, OF ROSELLE PARK, NEW JERSEY, ASSIGNOR TO THE SINGER MANUFACTURING COMPANY, A CORPORATION OF NEW JERSEY.

COVERING-THREAD MECHANISM FOR SEWING MACHINES.

1,403,857.

Specification of Letters Patent.

Patented Jan. 17, 1922.

Application filed April 5, 1919. Serial No. 287,778.

To all whom it may concern:

Be it known that I, GEORGE S. GATCHELL, a citizen of the United States, residing at Roselle Park, in the county of Union and State of New Jersey, have invented certain new and useful Improvements in Covering-Thread Mechanisms for Sewing Machines, of which the following is a specification, reference being had therein to the accompanying drawings.

In sewing machines of the multi-needle seam-covering type such, for example, as used for joining and covering the abutted edges of cut knit goods, it is customary to provide, in addition to the reciprocating needles and complemental loop-taking means of the machine, a pair of oscillatory thread-fingers for laying covering threads back and forth across the line of seam-formation in advance of the needles, so that said threads will, in effect, be stepped over by the needles and stitched down to the upper side of the work, thereby serving to connect the outer needle-threads and acting to cover the abutted raw edges of material at the center line of the seam in the manner illustrated in my copending applications Serial No. 185,446, filed August 10, 1917, and Serial No. 223,112, filed March 18, 1918, the latter having matured into Patent No. 1,365,238, January 11, 1921.

In seams of this character, as heretofore made, the transversely extending portions of the covering threads are closely grouped in pairs or lie in side-by-side relation across the center line of the seam, so that the abutted raw edges of material are exposed at intervals between the pairs of transversely extending portions of the covering threads. The object of the present invention, therefore, is to provide an improved covering thread mechanism whereby the covering threads will be more evenly and uniformly distributed across the center line of the seam to better cover and bind down the abutted raw edges of material.

Further objects of the invention will appear from the following description and claims.

50 In carrying the invention into effect, provision is made for so holding the covering threads prior to the descent of the needles, that the outer needles descend in front of or, in effect, step over both covering threads 55 while an intermediate needle steps over only one of the covering threads, the other cover-

ing thread being held forwardly of the path of movement of said intermediate needle. The transversely extending portions of the covering threads are thus separated where they cross the center line of seam-formation, giving the covering threads a zigzag appearance along the central zone of the seam.

As a means for deflecting one of the covering threads forwardly of an intermediate needle, I employ in addition to the usual oscillatory covering thread-fingers, a thread positioning device secured preferably to the shank of the presser-foot and extending forwardly between one of the outer needles and an adjacent intermediate needle; said device presenting a substantially vertical thread-detaining edge formed preferably with a thread-receiving notch into which one of the covering threads is drawn by the movement of its oscillatory thread-finger and held in front of said intermediate needle while the remaining needles descend in front of said covering thread. During the formation of the next stitch the other of the two-thread-fingers carries its thread into engagement with the thread-positioning device with similar results.

As one of the thread-fingers oscillates at a slightly higher level than the other, a thread-depressor is provided for bending downwardly the thread leading from the work to the higher of the two thread-fingers when in extreme outward position.

In the accompanying drawings, Fig. 1 is a side elevation of the parts adjacent the stitching point of a sewing machine embodying the invention. Fig. 2 is a transverse vertical section through the free end of the work-arm of the machine; showing the stitch-forming instrumentalities in elevation. Fig. 3 is a horizontal section on the line 3—3, Fig. 1. Fig. 4 is a side elevation of the presser-foot of the machine, showing the thread positioner and thread depressor. Fig. 5 is a front elevation similar to Fig. 2 but showing how the thread-depressor is elevated by the advancing thread-finger. Fig. 6 is a perspective view of the thread-positioning device. Fig. 7 is a plan view of the seam formed by the machine illustrating the even distribution of the covering threads across the abutted raw edges of the material at the center line of the seam.

The invention will be described as embodied in the four-needle seam-covering machine disclosed in my said copending ap-

lication Serial No. 185,446. In a machine of this character the needle-bar 1 carrying a plurality of (in the present instance 4) needles n^1 , n^2 , n^3 and n^4 , is journaled for reciprocation in the head 2. The needles are arranged abreast transversely of the line of seam-formation and cooperate with the thread-carrying looper 3 to form a seam of the usual character comprising a plurality 10 of needle-threads formed at intervals into loops extending through to the under side of the work and concatenated with a single looper-thread which is looped back and forth across the seam and covers the abutted raw edges of material at the center line.

The machine also embodies a pair of oscillatory thread-fingers 4^a and 4^b for looping a pair of "flier" or covering threads back and forth across the upper side of the seam. The covering thread fingers 4^a and 4^b are preferably formed with horizontally disposed blades and vertically disposed shanks; the latter being secured in socketed bosses 5 at the free ends of the thread-finger carrying levers 6, the opposite apertured ends of which are fulcrumed upon the lower reduced end of a bushing or sleeve 6^x surrounding and slidably receiving the presser-bar 7 which carries the usual hinged presser-foot 8.

The blades of the thread-fingers 4^a and 4^b are preferably curved to the same radius concentric with the presser-bar, Fig. 3, and are formed at their free ends with thread-delivering eyes 9 which are connected by thread-grooves 10 with the thread-eyes 11 at the lower ends of the vertical shank portions of the thread-fingers. The blades of the thread-fingers operate at different levels, 35 one being slightly above the other.

Simultaneous oscillatory movements in opposite directions are imparted to the levers 6 by means of the links 6^a which connect the latter with one arm 6^b of a bellcrank-lever fulcrumed on the headed pin 6^c carried by the head 2. The other arm 6^d of the bellcrank-lever is connected to suitable actuating mechanism 6^e, such for example as disclosed in my said copending applications, 45 for imparting oscillatory movements to the thread-fingers at one-half the frequency of reciprocation of the needles, so that each thread-finger presents its thread to the needles alternately at opposite sides of the line of seam-formation.

The customary feeding devices or dogs f are provided for advancing the work up to and beyond the stitching point.

In mechanism of this character, as heretofore constructed and operated, the covering threads are led in opposite directions across the seam in advance of the needles so that when the needles rise and the feed takes place, the covering threads will be 60 shifted back of the needle paths and the

needles on their next descent will all pass down in front of the covering threads, thus binding together in pairs the transversely extending portions thereof.

In the present instance, a covering thread 70 positioning device is provided for holding one of the covering threads in advance of the path of an intermediate needle while permitting said covering thread to assume a position in rear of the remaining needle-paths. While various thread-positioning devices may be used to accomplish this purpose, a simple form of such device is shown in perspective in Fig. 6. The device in this form comprises a thin blade 12 present- 75 ing a vertically disposed thread-positioning edge 13 which is preferably formed with a notch 14 into which the covering thread is laid by one or the other of the thread-fingers 4^a and 4^b. The blade 12 is supported by a 80 plate-like shank 15 which is fixed to the shank of the presser-foot 8 by a screw 16. As shown in Figs. 2, 3 and 5, the thread-positioning device 12 is placed between the outer needle n^4 and the adjacent intermediate needle n^3 but closer to the latter, with the thread-engaging edge 13 and notch or throat 14 in advance of the plane of the needles.

When the thread-fingers are crossing the 95 line of seam, the covering thread leading from one or the other of the eyes 9 will be drawn across the edge 13 of the positioning device 12 and, as the thread-finger assumes extreme position, the covering thread will 100 slip into the notch 14 and be detained in the form of a bight or peak in advance of the path of needle n^3 but in rear of the paths of needles n^1 , n^2 and n^4 , as shown in Figs. 2 and 3. The other covering thread 105 will not be engaged by the positioning device and will lie in rear of all of the needle-paths. The two transversely extending portions of the covering threads will thus be separated by the penetrative thread-loops of 110 the intermediate needle n^3 and will be evenly distributed across the abutted raw edges of the material along the center line of the seam, as illustrated in Fig. 7.

In some instances it may be desirable to 115 provide a device to compensate for the difference in elevation of the thread-eyes 9, 9, at the free ends of the covering thread-fingers. Such a device may comprise a thread-depressor in the form of a curved 120 blade 17 having at its downturned free end an upwardly and rearwardly inclined thread-engaging edge 18. The blade 17 may be supported by a cylindrical shank 19 journaled to turn in spaced bearings 20 at the lower edge of a supporting plate 21 fixed by screws 23 to the flattened face of a collar 22, Figs. 3 and 4, clamped to the lower end 125 of the sleeve 6^x.

The shank 19 is surrounded by a coiled 130

spring 24, Fig. 1, the opposite ends of which are anchored, respectively, to one of the bearing lugs 20 and to a collar 25 fixed to the shank 19 adjacent the other of the bearing lugs 20. This spring tends to yieldingly turn the shank 19 in a direction to depress the free end of the curved blade 17, the inclined edge 18 of which depresses and deflects rearwardly one of the covering threads, as shown in Figs. 1 and 2. When the thread-finger 4^a advances, the curved blade 17 is elevated thereby to an ineffective position wherein the blade rests yieldingly against the upper surface of the horizontal portion of the thread-finger 4^a. The primary purpose of the blade 17 is to compensate for the difference in elevation of the thread-eyes 9, 9, at the period of the cycle illustrated in Fig. 2, by depressing the covering thread leading from the work to the thread-finger 4^a so that this covering thread will lie below and out of contact with the thread-positioning plate 12.

It is to be understood that the use of the depressor is not absolutely essential; it being merely a desirable feature, in certain instances, where the dimensions of the parts and the throw and extent of movement of the thread-fingers are such that the covering thread leading to the higher of the two thread-eyes 9 is not held clear of the thread-positioning device 12.

In the seam formed by the present device it will be noted that one of the covering threads *a* extends across the seam in the front of the transverse row of needle-punctures *b* and in rear of the next succeeding transverse row of needle-punctures *b'* crossing the center line *c* of the seam at *d*. The covering thread *a'*, however, while extending transversely of the seam in front of the needle-punctures *b* and behind three of the needle-punctures *b'*, is deflected or held forwardly of an intermediate needle-puncture *b'* and is thus separated from the covering thread *a* and caused to cross the abutted raw edges of the material at the point *d'* which is spaced from the point *d*. Thus the points where the covering threads cross the center line of the seam will be evenly distributed along the latter; the covering threads along the central zone of the seam having a zigzag appearance and effectively covering and binding down the cut thread ends along said center line.

Having thus set forth the nature of the invention, what I claim herein is—

1. In a sewing machine, in combination, a plurality of reciprocating needles, complementary loop-taking means, feeding mechanism, means for laying a covering thread back and forth across the line of seam-formation, and a thread-positioner restrained against movement in the direction of feed and operating to hold the covering

thread forwardly of the path of movement of one of said needles while others of the needles descend in advance of said covering thread.

2. In a sewing machine, in combination, a plurality of reciprocating needles, complementary loop-taking means, feeding mechanism, means for laying a plurality of covering threads back and forth across the line of seam-formation, and a thread-positioner for holding one of the covering threads forwardly of the path of movement of an intermediate needle while others of the needles descend in advance of the covering threads.

3. In a sewing machine, in combination, three or more reciprocating needles, complementary loop-taking means, feeding mechanism, a pair of oscillatory thread-fingers for laying covering threads back and forth across the line of seam-formation, and a covering thread positioning device disposed between an outer and an intermediate needle and having a thread-deflecting surface in advance of and close to said intermediate needle for holding the covering thread in advance of the latter while the remaining needles descend in advance of the covering threads.

4. In a sewing machine, in combination, a plurality of reciprocating needles, complementary loop-taking means, a presser-foot, feeding mechanism, means for laying a covering thread back and forth across the line of seam-formation, and a covering thread positioning device mounted upon said presser-foot and extending forwardly between the paths of an outer and an intermediate needle, substantially as and for the purpose specified.

5. In a sewing machine, in combination, a plurality of reciprocating needles, complementary loop-taking means, feeding mechanism, a covering-thread laying element, and a covering-thread positioning device projecting forwardly intermediate the needle paths and adapted to engage the covering-thread in advance of the stitching point, substantially as and for the purpose specified.

6. In a sewing machine, in combination, a plurality of reciprocating needles, complementary loop-taking means, feeding mechanism, a covering-thread laying element, and a covering-thread positioning device permanently disposed intermediate the needle paths and adapted to engage the covering-thread in advance of the stitching point, substantially as and for the purpose specified.

7. In a sewing machine, in combination, a plurality of reciprocating needles, complementary loop-taking means, feeding mechanism, a covering-thread laying element, and a substantially stationary covering-thread positioning device adapted to engage the

covering-thread in advance of the stitching point and hold said covering-thread in advance of the path of a descending needle.

8. In a sewing machine, in combination, 5 three or more reciprocating needles, complementary loop-taking means, feeding mechanism, a pair of covering-thread fingers moving simultaneously in opposite directions back and forth across the line of seam- 10 formation in advance of the needles and at half the frequency of reciprocation of the needles, and a thread-positioning device co-operating alternately with each of said thread-fingers to detain first one and then 15 the other of the covering-threads in advance of an intermediate needle-path while the remaining needles descend in advance of the covering-threads.

9. In a sewing machine, in combination, 20 stitch-forming mechanism including a plurality of reciprocating needles and complementary loop-taking means, a covering-thread finger, means for moving said finger back and forth across the line of seam-formation in advance of the needles, a thread 25 positioner cooperating with said thread-finger in one extreme position of the latter to hold the covering thread in advance of one of said needles, and a device for holding 30 the covering thread clear of said thread positioner when said thread-finger is in its other extreme position.

10. In a sewing machine, in combination, 35 stitch-forming mechanism including a plurality of reciprocating needles and complementary loop-taking means, a covering-thread finger, means for moving said finger back and forth across the line of seam-formation in advance of the needles, and a 40 yielding device for depressing the covering-thread when the thread-finger is in an extreme position.

11. In a sewing machine, in combination, 45 stitch-forming mechanism including a plurality of reciprocating needles and complementary loop-taking means, a covering-thread finger, means for moving said finger back and forth across the line of seam-formation in advance of the needle, and a yielding 50 device for depressing the covering-thread when the thread-finger is in an extreme position, said device being disposed

in the path of movement of said thread-finger so as to be elevated thereby to ineffective position.

12. In a sewing machine, in combination, 55 stitch-forming mechanism including a plurality of reciprocating needles and complementary loop-taking means, feeding mechanism, a pair of oscillatory thread-fingers 60 having thread-delivering eyes operating at different levels, and a covering-thread engaging device cooperating with one of said thread-fingers to shift the covering-thread leading from the eye thereof to the work 65 sufficiently to compensate for the difference in elevation of said thread delivering eyes.

13. In a sewing machine, in combination, 70 stitch-forming mechanism including a plurality of at least three reciprocating needles and complementary loop-taking means, feeding mechanism, a pair of oscillatory thread-fingers having thread delivering eyes operating at different levels, a thread-positioning device for detaining the covering-thread 75 of one finger in advance of an intermediate needle while the remaining needles descend in advance of the covering-threads, and a covering-thread engaging device cooperating with the other of said thread-fingers to hold 80 the thread thereof clear of the thread-positioning device.

14. In a sewing machine, in combination, 85 a plurality of reciprocating needles, a presser-foot, feeding mechanism, means for laying a covering thread back and forth across the line of seam formation, and a covering thread positioning device stationarily mounted on the presser-foot and formed with a throat adapted to receive a bight of 90 covering thread and position it in advance of one of said needles.

15. In a sewing machine, in combination, 95 a plurality of reciprocating needles, a presser-foot, feeding mechanism, means for laying a covering thread back and forth across the line of seam formation, and a stationary covering-thread positioning device mounted on the presser-foot and formed with a throat into which the covering-thread is 100 laid by the covering-thread laying means.

In testimony whereof, I have signed my name to this specification.

GEORGE S. GATCHELL.
